UNITED STATES PATENT OFFICE.

FREDERIC SCHAEFER, OF PITTSBURGH, PENNSYLVANIA.

BRAKE-ROD JAW.

1,411,873.

Specification of Letters Patent.

Patented Apr. 4, 1922.

Application filed July 10, 1919. Serial No. 309,916.

To all whom it may concern:

Be it known that I, FREDERIC SCHAEFER, a resident of Pittsburgh, in the county of Allegheny and State of Pennsylvania, have 5 invented a new and useful Improvement in Brake-Rod Jaws, of which the following is a specification.

This invention relates to brake rod jaws and is an improvement upon my Patent No. 10 1,259,676 of March 19, 1918. The object of the improvement is to provide a brake rod jaw which can be more easily assembled with the brake rod than the one of the aforesaid patent, and in which integral means are provided 15 for positively engaging the free end of the hook on the brake rod to positively hold said hook against opening up even under abnormal strains.

In the accompanying drawings Fig. 1 is 20 a plan view of the jaw with the brake rod attached thereto; Fig. 2 is a side view thereof showing in dotted lines the wings prior to bending to final form; Fig. 3 is a longitudinal section therethrough on the line 25 3—3, Fig. 1; and Fig. 4 is a transverse view on the line 4—4, Fig. 3.

The jaw is formed from a single piece of metal, preferably a rolled plate of rectangular outline, although if desired the plate 30 may be sheared somewhat to the form of the blank to which it is forged. This plate is then subjected to the action of suitably formed dies which trim it out and shape it, the same having the two legs or jaw members 1 and 2 provided at their free ends 35 with the pin eyes 3, and at their other ends being joined to the web portion 4, which may be bent downwardly or slightly concaved on its upper surface. The extreme 40 end portion of the plate or blank is pressed upwardly, forming an upwardly bowed portion 5, whose inner edge, in the method of forming, is connected to the outer end of the web portions 4, by a thin inclined web which 45 is afterwards punched out to form the space or hole 7. In the die operation the excess metal from the trimmed out or cut away portions is caused to flow into the blank so as to form thickened portions at certain 50 points, to add strength and filling or spacing portions where required.

For example, the metal around the pin eyes 3 is caused to flow in both directions, forming a broadened bearing 8 for the connecting pin; the edges of the jaw portions 1 and 2 are also thickened or flanged as at

10, to strengthen these members; and the metal between the two limbs or jaw members 1 and 2 is in part forced into the web portion 4, providing bosses or protuberances 11 60 and 12, respectively on the upper and lower faces of the web portion 4, and providing a thickened edge for the brake rod hook at that point. The web portion 4 is inclined slightly toward its outer end, as shown in 65 Figs. 2 and 3, and on the bottom face at its outer end is provided with a boss thickened portion 13 forming a bearing for the brake rod. The outer upwardly bowed portion 5 will preferably be provided on both edges 70 with wings 14 and 15, which are of considerable length and having their adjacent edges beveled as indicated in Fig. 1 so that when bent around the brake rod they will lap past each other.

The blank is forged in the flat and afterwards the jaw members 1 and 2 are bent out of the plane in which they lie into substantially parallel planes at right angles to the original plane.

The brake rod 17 is assembled with the jaw in the following manner: The end of said rod, after heating, has its end bent backwardly upon itself to form an open hook, but with the free end 18 of the hook 85 separated from the body of the rod for a distance at least equal to the thickness of the portions 11 and 12. This hook is then entered between the two limbs 1 and 2, with the body of the rod lying below the web 90 portion 4, and said rod and jaw are then moved longitudinally of each other to cause the web 4 to enter into the hook, and by means of a hammer or the like the end 18 of the hook is closed downwardly until it 95 can enter the hole 7 between the web 4 and the upwardly bowed portion 5, and is forced through said hole until the root or inner curve of the hook takes bearing against the rounded portions 12 and 13, on the inner end of the web. The two wings 14, 15 are then bent downwardly, in opposite directions, around the body of the rod, lapping 100 past each other as shown to securely bind the hooked end of the rod in place.

In the improved jaw the center line of the body of the rod 17 is in exact alignment with the center of the pin eyes 3. The web portion 4 lies substantially in the plane of the original blank, being only slightly 110 curved downwardly, therefrom, while the upwardly bowed portion 5 (which is an

integral portion with the jaw itself) engages the free end of the hook and therefore holds said free end securely against opening up. Consequently the hook is not liable to fail even under abnormal strains.

5 The thickened portions 11, 12, at the inner end of the web provide an ample bearing for the hook, and the lug 13 on the lower face of the web at its outer end, together with the lug 12 at the inner end of said web, 10 tend to keep the jaw in exact alignment with the center line of the brake rod, so that there can be no twisting movement and no oblique straightening under the stresses in 15 abnormal use.

In the forging of the blank a thin web joining the inner edge of the upwardly bowed portion 5 and the outer end of web 4 is always left, and this is afterwards 20 punched out to form the hole 7. This hole therefore can be punched to various sizes, so as to adapt it to the diameter of the particular brake rod to be utilized, and therefore giving a relatively tight fit of the 25 free end of the hook of the brake rod in said opening, so that there is no substantial lost motion here which might have a tendency to allow the hook to have an initial opening or bending movement under abnormal stress. Furthermore, the slight flange 30 left around the hole 7 after punching out said thin web, forms points of contact with the free end of the hook and further assists in preventing the starting of any opening 35 movement of the hook.

The jaw described can be very readily formed by a die forging operation from a flat blank, without excessive waste of metal, and at a minimum labor cost. At the same 40 time it can be made of ample strength in all parts.

I claim:

1. In combination, a brake rod jaw composed of wrought metal and comprising jaw members lying side by side and united by a transverse web portion serving as a means for connecting a hooked brake rod end and having an upwardly bowed portion extending from said web portion and having 45 a hole therein, and a brake rod having a hooked end engaging said transverse web portion and with the body of the rod lying against one face of the said web portion and the free end of the hook entering the hole 50 in said upwardly bowed portion.

2. In combination, a brake rod jaw composed of wrought metal and comprising jaw members lying side by side and united by a transverse web portion serving as a means 55 for connecting a hooked brake rod end and having an upwardly bowed portion extending from said web portion and providing a hole therein, a brake rod having a hooked end engaging said transverse web portion 60 and with the body of the rod lying against

one face of the said web portion and the free end of the hook entering said hole, and a wing integral with said upwardly bowed portion and arranged to be bent around the body of the rod.

3. In combination, a brake rod jaw composed of wrought metal and comprising jaw members lying side by side and connected by a transverse web portion having upwardly and downwardly projecting rounded lugs at its inner end forming a thickened bearing for engagement with a hooked brake rod and having outwardly from said web portion an upwardly bowed portion, and a brake rod having a hooked end engaging the thickened bearing end of said web portion, with its body lying against one face of said web portion and its free end entering the space between the end of said web and the upwardly bowed portion.

4. In combination, a brake rod jaw composed of wrought metal and comprising jaw members lying side by side and connected by a transverse web portion having upwardly and downwardly projecting rounded lugs at its inner end forming a thickened bearing for engagement with a hooked brake rod and having outwardly from said portion an upwardly bowed portion, and a brake rod having a hooked end engaging the thickened bearing end of said web portion, with its body lying against one face of said web portion and its free end entering the space between the end of said web and the upwardly bowed portion, and a wing integral with the upwardly bowed portion and arranged to be bent around the body of said rod.

5. A brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, said jaw at its outer end having an upwardly bowed portion spaced from said transverse web portion and arranged to receive the free end of a brake rod hook.

6. A brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, said jaw at its outer end having an upwardly bowed portion.

portion spaced from said transverse web portion and arranged to receive the free end of a brake rod hook, and a wing integral with the upwardly bowed portion and arranged to be bent around the brake rod.

7. In combination, a brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, 30 said jaw at its outer end having an upwardly bowed portion spaced from said transverse web portion, a brake rod having a hooked end engaging the thickened bearing on the transverse web portion and having 35 its body bearing against the downwardly projecting lugs on said web portion and its free end extending through said space, and a wing integral with the upwardly bowed portion and arranged to be bent around the 40 body of said brake rod.
- 10 8. In combination, a brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, 30 said jaw at its outer end having an upwardly bowed portion spaced from said transverse web portion, a brake rod having a hooked end engaging the thickened bearing on the transverse web portion and having 35 its body bearing against the downwardly projecting lugs on said web portion and its free end extending through said space, and a wing integral with the upwardly bowed portion and arranged to be bent around the 40 body of said brake rod.
- 15 9. In combination, a brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, 30 said jaw at its outer end having an upwardly bowed portion spaced from said transverse web portion, a brake rod having a hooked end engaging the thickened bearing on the transverse web portion and having 35 its body bearing against the downwardly projecting lugs on said web portion and its free end extending through said space, and a wing integral with the upwardly bowed portion and arranged to be bent around the 40 body of said brake rod.
- 20 10. In combination, a brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, 30 said jaw at its outer end having an upwardly bowed portion spaced from said transverse web portion, a brake rod having a hooked end engaging the thickened bearing on the transverse web portion and having 35 its body bearing against the downwardly projecting lugs on said web portion and its free end extending through said space, and a wing integral with the upwardly bowed portion and arranged to be bent around the 40 body of said brake rod.
- 25 11. In combination, a brake rod jaw composed of wrought metal and comprising jaw members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, 30 said jaw at its outer end having an upwardly bowed portion spaced from said transverse web portion, a brake rod having a hooked end engaging the thickened bearing on the transverse web portion and having 35 its body bearing against the downwardly projecting lugs on said web portion and its free end extending through said space, and a wing integral with the upwardly bowed portion and arranged to be bent around the 40 body of said brake rod.

members lying side by side and connected by a transverse web portion inclined from its inner to its outer end and provided at its inner end with upwardly and downwardly projecting bosses forming a rounded thickened bearing for a brake rod hook and at its outer end with a downwardly projecting lug in substantial alignment with the downwardly projecting lug at its inner end, 30 said jaw at its outer end having an upwardly bowed portion spaced from said transverse web portion, a brake rod having a hooked end engaging the thickened bearing on the transverse web portion and having 35 its body bearing against the downwardly projecting lugs on said web portion and its free end extending through said space, and a wing integral with the upwardly bowed portion and arranged to be bent around the 40 body of said brake rod.

In testimony whereof, I have hereunto set my hand.

FREDERIC SCHAEFER.
